Primary Examiner — Jack Reickel(74) Attorney, Agent, or Firm — Eversheds Sutherland (US) LLP(57) CLAIM

The ornamental design for a display screen with a graphical user interface, as shown and described.

DESCRIPTION

The sole FIGURE is a front view of a display screen with a graphical user interface showing the claimed design.

The broken line showing of the display screen with a graphical user interface is included for the purpose of illustrating portions of the article and forms no part of the claimed design.
